UNITED STATES PATENT OFFICE.

DANIEL L. HOLDEN, OF NEW YORK, N. Y., AND LEMUEL W. SERRELL, OF PLAINFIELD, NEW JERSEY, ASSIGNEES TO KATHRYN M. HOLDEN, OF NEW YORK, N. Y.

ICE-MAKING APPARATUS.

SPECIFICATION forming part of Letters Patent No. 530,527, dated December 11, 1894.

Application filed June 19, 1893. Renewed May 5, 1894. Serial No. 510,227. (No model.)

To all whom it may concern:

Be it known that we, DANIEL L. HOLDEN, residing at the city and State of New York, and LEMUEL W. SERRELL, residing at Plainfield, 5 in the county of Union and State of New Jersey, both citizens of the United States, have invented an Improvement in Ice-Making Apparatus, of which the following is a specification.

10 In Letters Patent No. 490,475, granted January 24, 1893, to said Daniel L. Holden, an apparatus is represented in which the ice as it is formed upon a refrigerating surface is removed or scaled off by a revolving device, 15 and in his application, Serial No. 429,514, filed April 18, 1892, such ice floats in the water and passes over the edge or dam and is received into a holder or press containing a plunger by which the particles of ice are forced into 20 intimate contact and congeal into a block that is projected out of the trunk or press and cut up into sections. In apparatus of this character difficulty has been experienced in removing bubbles of air that adhere to the particles of ice as they pass over the dam and into the press and hence the ice as it is pressed into a block and consolidated is not always 25 clear and transparent.

The object of the present invention is to exclude bubbles of air from the particles of ice from the time that the water is frozen until the particles of ice are consolidated and also to give a free escape to such particles of air or fixed gases as may be developed in the 30 freezing operation, so as to displace such air or gases by water which is present during the consolidating operation that takes place below the surface of the water in the apparatus.

In carrying out this operation an apparatus 35 may be employed of any suitable construction and the devices herein represented are illustrative of an apparatus adapted to this improved method.

In the drawings, Figure 1 is a cross section 40 of said apparatus. Fig. 2 is a longitudinal section on a smaller scale at the line $\alpha\alpha$. Fig. 1. Fig. 3 is a partial sectional plan at

the line $y\gamma$, and Fig. 4 is a similar view at the line $z\zeta$. Fig. 5 shows the lower end of the ice trunk. Fig. 6 is a longitudinal section, and Fig. 7 is a cross section of a modification.

It is advantageous to employ brine that is caused to circulate through the apparatus, and this brine is reduced in temperature considerably below the freezing point in any well known refrigerating device, usually however by the action of ammonia within pipes that pass through the brine holding vessel, and the brine may be caused to circulate by the 55 action of a pump or otherwise.

The vessel A is adapted to receive water by the pipe F, and in this vessel there are represented a series of hollow cylinders G lying horizontal and having tubular journals at the 60 respective ends extending through the vessel A and driven by suitable gearing, such as indicated at H, and the brine supplying pipes are shown at C passing through the hollow journals at one end and passing out of such 65 cylinders by the pipes C² at the other end, or any suitable arrangement may be employed for supplying and removing the brine or other refrigerating material from the hollow cylinders G, and any suitable scrapers may be 70 provided for removing the ice in chips or scales from the surfaces of the hollow cylinders G. We have represented the scrapers E as adapted to this object.

In any apparatus that may be employed for 75 the purpose of freezing the water upon the refrigerating surfaces and removing the ice in scales or chips, the ice making devices are entirely below the surface of the water and the ice floats and accumulates in the upper 80 portion of the apparatus, and any suitable cover may be provided for the vessel A.

In Figs. 1 and 2 the perforated incline I is represented so that the particles of ice will accumulate at or near one side of the vessel 85 A, and such particles of ice will pass through the outlet K into the press L, which press is represented as vertical.

In this apparatus the scales or particles of

ice always remain below the water level, and the tendency of such ice being to float, causes it to accumulate in the upper part of the water holding vessel and pass up from time to time into the trunk L of the press so that the piston or plunger N as it is reciprocated will not only press upon the particles of ice that float up into the trunk L for consolidating the same and moving the block of ice down progressively in such trunk, but any particles of air or gas that may remain between the particles of ice will rise up in the water holding vessel and the water which may remain between the particles of ice as pressed will pass out through the perforated plunger N so that the ice will be free from bubbles and will be clear and transparent throughout.

In the apparatus represented the parts are arranged in a convenient manner for use, but this method of forming ice artificially may be carried out in any suitable apparatus. We find it advantageous to place the horizontal cylinders G in ranges sufficiently far apart to give access between them for repairs and to rotate the cylinders in opposite directions as indicated by the arrows, and the scrapers E are represented in Figs. 1 and 2 as supported upon cross shafts 4 that have eyes at their ends sliding upon the stationary bars 5, and these cross shafts 4 and scrapers E are moved progressively from end to end upon the cylinders G by any suitable means, such for instance as the endless chains 6 which pass around sprocket wheels 7 upon shafts 8 that project through packing boxes or bearings upon the vessel A and they are driven by suitable power applied to pulleys 9 upon their outer ends; and it is advantageous to employ the reversing devices such as common in planing machines and presses, for changing the direction of rotation of the pulleys 9, and with this object in view the fingers 10 projecting from the shafts 4 act upon arms 11 projecting from the rock shafts 12 when the scrapers reach the respective ends of their movements, so that by these rock shafts 12 any suitable mechanism may be actuated for reversing the direction of rotation of the pulleys 9 and thereby moving the scrapers E first in one direction and then in the other.

By placing the scrapers E in pairs, as shown, the strain upon each scraper as it is held to position will be taken in the opposite direction by the other scraper to hold that in position, thus lessening the lateral thrust upon the bars 5. In Fig. 1 the positions of the gears H are represented by dotted lines and the direction of rotation indicated by the arrows.

The incline I may be of sheet metal perforated with long and narrow openings, or slots close together may be employed, the object being to allow the escape of any air or fixed gases and at the same time to direct the particles of ice toward the opening K, and conveyer screws P may be made use of, standing

at opposite directions and rotated by suitable power, so as to tend to move the particles of ice toward the opening K to the press.

The piston N of the press is advantageously perforated on the end for the escape of water or any fixed gases upwardly as the piston is pressed down upon the particles of ice to consolidate the same, and the piston is hollow and provided with openings for the lateral discharge of water as the piston rises, and by connecting the trunk L of the press upon one side of the water vessels A, as shown, and prolonging the three sides of the press trunk L above the top of the vessel A, leaving the fourth side open at 13, the water which may be raised in the hollow piston can run out through the openings 14 and pass along the side channels 15 and run at the open side 13 into the water holding vessel A. We also find it advantageous to make use of the detaining clips 16 bolted to the lower end of the press trunk L and set up by screws 17 so that the clips are slightly closer together than the width of the press trunk L. Thereby said detaining clips 16 apply sufficient detaining force to the ice as it is pressed to firmly consolidate the same and to prevent the block of ice falling away by gravity out of the trunk when the lower end is unsupported; and by providing a saw the ice can be sawed off in blocks of the desired length and allowed to slide away upon a suitable chute to the storage room. We also find it advantageous to make use of hydraulic power for moving the piston N, because such piston N can remain stationary at any point after the given pressure has been exerted upon the ice, and as the piston is drawn up the ice which has accumulated adjacent to the opening K will pass into the press trunk L and be in a position to be forced downwardly by the action of the piston N, and should it be desired, a gate can be applied, as illustrated by the dotted lines at 18, the same being moved down to close the opening K before the piston N is actuated, thereby retaining the particles of ice within the press trunk, and under all circumstances the freezing of the water, the scaling off of the ice in chips and the pressing of the chips into blocks of ice takes place below the surface of the water, so that the presence of bubbles in the ice is almost wholly avoided and the ice can be manufactured with great rapidity because only a thin layer of ice intervenes between the water and the frigerific surface, and there is no loss of water, the same being returned into the vessel from the press and the supply of water coming in at the bottom becomes gradually cooled so that the water at the top of the vessel A and the floating ice can be below the freezing temperature.

We find great advantage in only freezing a comparatively thin layer of ice upon the surfaces of the cylinders G, because the thicker the layer of ice is the less efficient is the re-

frigerating operation because the layer of ice intervening between the cold surface and the water causes the ice to form more slowly as the thickness of the layer increases.

5 The modification in the scrapers represented in Figs. 6 and 7 consists in moving the scrapers by a continuous progressive movement instead of a reciprocating movement. In this instance the scrapers E' are 10 upon the chains 16 that travel along upon ways or supports 17, and such scrapers or cutters E' are connected with the chains and pass at the ends around the pulleys or sprocket wheels 18 and travel in the opposite direction 15 and act upon the lower cylinders G, as indicated by the arrows, and the shape of the cutters or scrapers E' and the angle at which they stand to the surfaces of the cylinders are to be such that the cutting edges will run 20 in close proximity to the surfaces of the cylinders without injury to the metal of such cylinders.

If the top of the water holding vessel A is arched or made as a double incline, the particles of ice may be taken off at the end of the vessel instead of at the side, and the trunk or press may be placed either vertically, as shown, or in any other desired position so long as the pressing operation is 30 performed beneath the surface of the water.

It is a well ascertained fact that water expands as it freezes and that when pressure is applied to ice the tendency is to cause the ice to liquefy and return to water, even though the temperature may be considerably below the freezing point. This fact is availed of in the present improvement because when the pressure is applied to the particles of ice having the interstices filled with water the 40 tendency is for the ice to liquefy by the pressure, and hence the block of ice consolidates with uniformity as the pressure is relieved.

In running this apparatus it is desirable to proportion the speed of the pressing device so as to act upon the particles of ice before there is time for the intervening water to congeal; or in other words, it is advantageous to supply sufficient water at an ordinary temperature at the bottom of the apparatus for such 50 water to become cool and to congeal upon the refrigerating surfaces and for the ice to be sealed off and ascend with the water which expands as it becomes cooler and hence rises with the ice, and the mass of ice particles and intervening water should be taken off by the press with such rapidity that the mass cannot con-

geal in the water holding vessel but will congeal in the press under the action of the plunger.

We claim as our invention—

1. The method herein specified of making ice, consisting in exposing water to a refrigerating surface upon which ice is formed, sealing or cutting off such ice, allowing the particles of ice to rise in the water, receiving 65 such particles of ice into a suitable trunk or press below the surface of the water, and consolidating the particles of ice by pressure and discharging the surplus water from between the particles of ice, substantially as set forth. 70

2. The combination in an ice making apparatus, of a water holding vessel, refrigerating surfaces upon which the water is frozen, mechanism for cutting or sealing the ice from said surfaces, a trunk or receiving vessel below the water line into which the particles of ice are passed, and a piston for consolidating the particles of ice, there being openings for the escape of surplus water in consolidating the ice, substantially as set forth. 75

3. The method herein specified of making blocks of ice, consisting in freezing water, passing the scales or particles of ice into a trunk or holder beneath the surface of the water, and pressing such particles of ice while 85 excluded from the atmosphere to consolidate the same, and form blocks, substantially as set forth.

4. The method herein specified of making blocks of ice, consisting in freezing water, 90 passing the scales or particles of ice into a trunk or holder with the interstices between the ice filled with water to exclude atmosphere and pressing the mass to consolidate the ice and discharge the surplus water, sub- 95 substantially as set forth.

5. The combination in an ice making machine, of a refrigerating surface upon which the water is frozen, cutters for cutting or sealing the ice from such surface, a press for consolidating the particles of ice, and an opening 100 from the refrigerating vessel into the press below the surface of the water for the particles of ice to pass into the press without coming in contact with the atmosphere, substan- 105 tially as set forth.

Signed by us this 16th day of June, 1893.
